FLIER WIRE TRAVELER.

1,323,594.

Specification of Letters Patent.

Patented Dec. 2, 1919.

Application filed November 21, 1918. Serial No. 263,552.

To all whom it may concern:

Be it known that I, JOHN C. HOUCK, Jr., a citizen of the United States, residing at Dorranceton, in the county of Luzerne and 5 State of Pennsylvania, have invented certain new and useful Improvements in Flier Wire Travelers; and I do hereby declare the following to be a full, clear, and exact description of the invention, such as will enable others skilled in the art to which it 10 appertains to make and use the same.

The present invention relates generally to the art of spinning, and aims to provide a novel and improved flier wire traveler attachment for bobbin spindles used for twisting silk, cotton or other yarn.

These flier wire travelers are used on spindles above the bobbins of yarn thereon and are free to turn about the spindle as 20 the spindle and bobbin are rotated at a high velocity to put the twist in the yarn as it is run from the bobbin, it being the function of the traveler to guide the yarn from the bobbin with minimum friction, for which 25 reason the traveler is free to turn as the yarn is unwound. Such travelers are used extensively and have up to the present been a source of inconvenience due to the cost thereof and difficulty in replacing the worn 30 out wire.

The invention has for its object the provision of novel yet simple and effective means for mounting a flier wire traveler on the spindle above the bobbin, so as to enable 35 the traveler to rotate freely and to also permit it to be quickly removed and replaced by movement laterally of the spindle or supporting member, the present construction being extremely inexpensive.

With the foregoing and other objects in view which will be apparent as the nature 40 of the invention is better understood, the invention resides in the construction and assemblage of the component elements as hereinafter described and claimed, it being understood that changes can be made within the scope of what is claimed without departing from the spirit of the invention.

The invention is illustrated in the accompanying drawing wherein—

Figure 1 is a side elevation showing the flier wire traveler applied to the spindle over the bobbin.

Fig. 2 is a horizontal section on the line 55 2—2 of Fig. 1.

Fig. 3 is a view similar to Fig. 2 showing a double formation of the traveler.

In the drawing, the number 1 designates the usual bobbin fitting on the upstanding spindle 2 which is tapered so that the bobbin 60 fits tightly down to rotate therewith for putting the twist in the yarn. The traveler is formed of wire of any suitable quality, and comprises an arm 3 extending radially from the spindle 2 and provided at its outer 65 free end with a coil or loop forming a guide eye 4 through which the yarn 5 passes upwardly so as to keep the yarn out of contact with the upper flange of the bobbin spool, and thereby reduce friction to a minimum, said arm 3 being mounted to rotate 70 freely around the spindle as the yarn is unwound from the bobbin and pulled upwardly.

The gist of the invention resides in the 75 mounting of the traveler on the spindle, and to accomplish this result in a thoroughly practical and simple manner, a pivot or hub member 6 of wood, composition, metal or other suitable material is provided, said 80 member having a central tapered aperture so that it can be slipped down on the spindle to fit snugly thereon above the bobbin. It is an easy matter to remove the member 6 for the removal and replacement of the 85 bobbin, and members 6 of different sizes can be used interchangeably so as to accommodate bobbins which fit on the spindle 2 to different heights. This pivot member 6 is provided with an annular or circumferential groove 7 of slightly greater width 90 than the diameter of the wire from which the traveler is formed, and the inner end of the wire arm 3 has a loop 8 to fit in the groove 7 and loosely embrace the member 6 95 between the upper and lower flanges formed by the groove. This loop 8 extends through an arc of over one half of a circle, so as to snap over the reduced or neck portion of the member 6, and the arm 3 extends radially 100 from the loop 8, there being a bend between the arm and loop for this purpose. The other end of the loop has an out-turned portion 9 which projects out of the slot 7, and which forms with the arm 3 an entrance throat which is restricted between the ends of the loop 8. The arm 3 and portion or finger 9 diverge apart from the loop 8 so that when the traveler is to be attached to the pivot and supporting member 110

6, it is only necessary to pull the arm 3 tangentially across the member 6 within the groove 7 so that the loop 8 snaps onto the reduced or neck portion of said member. 5
 5 The traveler is then in position for operation and can rotate freely about the spindle 2 and member 6 with little or no friction. When the traveler is worn out, it can be readily removed by disengaging the loop 10 8 from the member 6, and this is facilitated by springing the arm 3 and finger 9 apart to open the throat of the loop. By having the member 6 made of wood or equivalent material, it has been found that there is 15 very little or negligible wear between the traveler and its mounting, and the member 6 can be used for a number of the travelers as they are worn out and replaced.

Fig. 3 shows the traveler as being of double formation, that is, it has two oppositely extending arms 3 and eyes 4 at their opposite ends, and the wire has loops 8 at the adjacent ends of the arms 3 integral so as to be of S formation. Either loop 8 can be 20 snapped into engagement with the member 6, the same as the loop 8 before described and when one eye 4 is worn out, then the traveler can be detached and loop 8 of the other arm applied to the member 6. This 25 doubles the life of the traveler.

Having thus described the invention, what is claimed as new is:

1. In a yarn spinning device, a supporting member having an annular groove, and 35 a flier traveler for the yarn having a loop to snap within and turn freely in said groove.

2. In a yarn spinning device, a supporting member having an annular groove, and 40 a flier wire traveler comprising an arm having an eye at one end and a loop at the other end extending through an arc of over one half of a circle to snap within and loosely embrace said member within the 45 groove.

3. In a yarn spinning device, a supporting member, and a flier traveler having a portion arranged to move laterally of said member, and snap around and frictionally 50 engage same so as to loosely embrace said

member and thereby support said traveler for rotation around said member and also hold the traveler to said member unaided and permitting the traveler to be snapped out of engagement from said member laterally thereof. 55

4. In a yarn spinning device, a supporting member having an annular groove, and a flier traveler having a portion arranged to move laterally of said member and snap 60 into frictional engagement with said member so as to loosely and detachably embrace said member within the groove to thereby support said traveler for rotation in said groove around said member and also hold 65 the traveler to said member unaided and permit the traveler to be snapped laterally out of engagement from said member.

5. In a yarn spinning device, a supporting member, a flier traveler formed of one 70 piece of wire having two loops between its ends to snap into and out of engagement with and loosely embrace said supporting member, and having arms extending from said loops. 75

6. In a yarn spinning device, a supporting member, a flier wire traveler comprising opposite arms and an S-shaped portion between the arms providing a pair of loops to snap into and out of engagement with 80 said supporting member for rotatably supporting the traveler.

7. A device of the character described comprising a member to fit on a spindle above a bobbin and having an annular 85 groove, and a flier traveler having a loop to snap into and out of engagement with the said member within the groove.

8. A device of the character described comprising a member having a tapered 90 aperture to fit snugly upon a spindle above a bobbin, and having an annular groove, and a flier wire traveler comprising a wire arm having an eye at one end and a resilient loop at the other end to snap into and out 95 of engagement with the said member within the groove.

In testimony whereof I have signed my name to this specification.

JOHN C. HOUCK, Jr.
